UNITED STATES PATENT OFFICE.

ELIZABETH MADDEX, OF TERRE HAUTE, INDIANA.

OVERALLS.

1,325,099.

Specification of Letters Patent. Patented Dec. 16, 1919.

Application filed October 18, 1918. Serial No. 258,689.

To all whom it may concern:

Be it known that I, ELIZABETH MADDEX, a citizen of the United States, and a resident of Terre Haute, in the county of Vigo 5 and State of Indiana, have invented certain new and useful Improvements in Overalls, of which the following is a specification.

This invention relates to overalls, and an object of the invention is to provide in the 10 construction of overalls, means to allow the leg portions thereof to be tightly bound about the wearer's legs below the knee, eliminating the necessity of the use of leggings or puttees in connection therewith and preventing the looseness and flapping movement of the lower leg portion, thereby adding 15 to the cleanliness of the overalls and keeping the leg portions at the bottom out of the wearer's way; and also to provide an 20 adjustable belt structure by means of which overalls may be drawn tightly about the wearer's waist if desired.

More specifically, the invention comprehends the provision of a strap structure including a pair of branch straps having their 25 face ends stitched in the seam of the leg portion of the overalls and their outer ends converging into a single strap which carries a suitable receiving portion of a snap or 30 fastening structure adapted for coaction with a companion or inserting portion carried by the leg portions of the overalls remote from the seam to which the straps are attached thereby allowing the lower leg 35 portions of the overalls to be bound tightly about the wearer's leg and to provide, in the single length portion of the strap means for adjusting the length of the straps to accommodate them for use upon different 40 sized persons.

Other objects of the invention will appear in the following detailed description taken in connection with the accompanying drawing, forming a part of this specification, 45 and in which drawing:

Figure 1 is a rear view of a man wearing the improved overalls.

Fig. 2 is a cross section through the waist portion of the overalls.

Fig. 3 is an enlarged detailed section 50 through one of the seams of the leg portions of the overalls illustrating the manner of connecting the strap thereto.

Fig. 4 is a cross section through one of 55 the leg portions of the overalls, showing the binding strap applied thereto, and

Fig. 5 is a fragmentary view of one of the binding straps of the leg portions of the overalls.

Referring more particularly to the drawing, 1 generically indicates the overalls which preferably have the waist portion 2 formed with or upon the leg or pants portion 3 thereof. The body of the overalls has a belt structure 4, attached thereto at the 60 waist line, the said belt being stitched to the overalls about the front portion and having its portions which extend rearwardly of the side seam of the overalls free from stitched connection therewith. The relatively short end 5 of the belt structure 4 which extends rearwardly from one of the sides of the overalls carries an inserting member 6 of a catch structure which is 65 adapted for insertion into the receiving member 7 of the catch structure which is carried by the terminal of the relatively long free portion 8 of the belt structure. The free end portion 8 of the belt structure 70 carries an adjusting clamp structure 9 similar to the adjusting clamp of ordinary suspenders, by means of which lengths of the relatively long ends 8 of the belt structure 75 may be adjusted as desired for regulating the snugness of the fitting of the waist portion of the overalls about the waist of the 80 wearer.

The leg portions of the overalls are provided with the usual and ordinary seams 10 and 11 and the binding strap structure 90 which is generically indicated by the numeral 12 and comprises the strap members 13 and 14 is connected to the leg portions at the seam 10, by the inserting of the ends of the straps 13 and 14 into the seam, as clearly 95 shown in Fig. 3 of the drawing, when forming the seam and stitched to the leg portion by the stitching of the same as clearly shown in Fig. 3 of the drawings, wherein it will be noted that the ends of the straps 13 and 14 extend inwardly and are folded over the overlapping portions of one of the edges of the leg portion, being engaged between the folded over seam portion of each of the pieces of which the leg portions are 100 formed, thus providing a secure connection between the strap and the overall leg. The straps 13 and 14 converge as they extend outwardly or away from the seams 10 and they have their outer portions stitched to 105 each other and to a length 15 of the strap as shown at 16. The length 15 of the strap 110

is provided with an adjusting clamp structure 17 of the ordinary type used on suspenders, supporters, and analogous structures for regulating the length of the free 5 end portions of the strap structure. A receiving or eye portion 18 of a clasp is carried by the folded over end of the strap 13 and is provided for receiving therein the 10 button or inserting member 19 of the clasp structure. This button or inserting member 19 is connected to the leg portions of the overalls, at the seam 11 as clearly shown in Fig. 4 of the drawings, so that when the 15 portions 18 and 19 of the clasp structure are connected, the leg portion of the overalls must be folded as shown in Fig. 4 of the drawings, to cause them to snugly fit about the legs of the wearer below his knees.

Changes in details may be made without 20 departing from the spirit of this invention, but

I claim:

1. In an overall structure, the combination with leg portions, of binding strap structures, each of said binding strap structures comprising a pair of straps having their ends stitched to each leg portion, said straps converging and having their free ends connected to a single strap section extending 25 outwardly from the converging ends, and clasping means for holding said straps about a wearer's legs.
2. In an overall structure, the combination with leg portions having the usual side 30 seams, of a binding strap having one end stitched to each leg portion at one of said seams, a clasp section carried by the free end of each strap, a companion clasp section carried by each leg portion at the other seam 35 for coaction with the strap carrying clasp sections whereby said leg portions may be tightly bound about a wearer's legs and means for adjusting the length of said strap.
3. In an overall structure, the combination 40 with leg portions having the usual side seams, of binding strap structures, each of said binding strap structures comprising a pair of straps having their ends stitched to one seam of each leg portion, said straps converging and having their free ends connected to a single strap section extending 45 outwardly from the converging ends and clasping means for holding said straps bound about a wearer's legs.
5. In an overall structure, the combination 50 with leg portions having the usual seams, of binding strap structures, each comprising a pair of straps having their corresponding ends stitched to one seam of each 55 of the leg portions, said straps converging and having their free ends connected and connected to a single strap section extending

outwardly from the connected converging ends, a clasp section carried by the free end of the said single strap section, and a companion clasp section carried by each leg portion at the other seam for coaction with the strap carried clasp structure whereby said leg portions may be tightly bound about a 65 70 wearer's legs.

5. In an overall structure, the combination with leg portions having the usual seams, of binding strap structures, each comprising a pair of straps having their corresponding ends stitched to one seam of each of the leg 75 portions, said straps converging and having their free ends connected and connected to a single strap section extending outwardly from the connected converging ends, a clasp section carried by the free end of the said 80 single strap section, and a companion clasp section carried by each leg portion at the other seam for coaction with the strap carried clasp structure whereby said leg 85 portions may be tightly bound about a wearer's legs, and means carried by said single strap sections for adjusting their length.

6. In an overall structure, the combination, with a leg portion thereof of a pair of binding straps having their corresponding 90 ends connected to said leg portion, one near the knee portion of the leg and one near the lower end thereof, said straps converging, a single strap attached to the converged end of said straps and clasping means carried by 95 said leg portion intermediate the knee portion and lower end thereof for engagement with the free end of said single strap.

7. In an overall structure, the combination, with a leg portion thereof, of a strap 100 connected to said leg near the knee portion thereof and inclining downwardly for downward spiral winding about the leg, a second strap connected to the leg near its lower end and inclining upwardly for upward spiral 105 winding about the leg, and means for connecting the free ends of said straps to the leg portions.

8. In an overall structure, the combination, with a leg portion thereof, of a strap connected to said leg near the knee portion and inclining downwardly for downward spiral winding about the leg, a second strap connected to the leg near its lower end and inclining upwardly for upward spiral winding about the leg, said straps having their 110 free ends connected, a single strap connected to said free end, clasping means carried by said leg portion intermediate the knee portion and lower end for engagement with the 115 free end of said single strap, and means for adjusting the length of said single strap.

ELIZABETH MADDEX.
